UNITED STATES PATENT OFFICE.

ROBERT BINNIE, OF BOLIVAR, PENNSYLVANIA.

DRILL.

SPECIFICATION forming part of Letters Patent No. 694,822, dated March 4, 1902.

Application filed September 5, 1900. Serial No. 29,055. (No model.)

To all whom it may concern:

Be it known that I, ROBERT BINNIE, a citizen of the United States, and a resident of Bolivar, in the county of Westmoreland and State of Pennsylvania, have invented a new and Improved Drill, of which the following is a full, clear, and exact description.

The purpose of this invention is to provide a drill adapted especially for work in coal, clay, and other soft minerals and which will have a drill-rod the movement of which adapts it to a bit of any character, either a boring-tool or a chiseling-tool. By this means if an ore ball or lump is struck the boring need not be abandoned, as heretofore, but a chiseling-tool may be applied and the work carried on as before.

This specification is the disclosure of one form of the invention, while the claims define the actual scope thereof.

Reference is to be had to the accompanying drawings, forming a part of this specification, in which similar characters of reference indicate corresponding parts in all the views.

Figure 1 is a front elevation of the invention. Fig. 2 is a view disclosing interior parts and showing the drill in a second position. Fig. 3 is a detail of the feed in side elevation, and Fig. 4 is a detail of the feed in top plan.

The drill is carried on posts 5, which support a transverse body-plate 6. One of the posts is adjustable toward and from the other by means of a bolt 7 on the clamp of such post, the bolt working in a slot 10 in the body-plate 6, and this slot also adjustably carries the bolt 8, which holds the frame-bar 9 of the drilling mechanism.

The working parts of the drill are inclosed in a housing 11, which is preferably made in sections and which has sliding movement on the frame-bar 9, which movement is guided and limited by bolts 12, fitting in a slot in the casing. A feed-screw 14 is held to turn in the upper end by the guide-bar 9 and is provided with a handle 15 for turning it. This screw passes loosely through two brackets 16 on the casing 11 and is engaged by a feed-nut 17, which is also a pinion and which is held to turn, but not to move, axially in the upper bracket 16. The drill-rod 18 is mounted to slide and to turn in the casing 11 and in the brackets 16 thereof, and a pinion 19, which is

splined on the drill-rod, meshes with the nut-pinion 17 to turn the same, and by these means the housing or casing 11 is moved on the frame-bar 9 to feed the drill-rod. The pinion 19 forms part of a worm-wheel 20, these parts being joined by a neck 21, which is arranged to turn in the upper bracket 16, and the whole being splined on the drill-shaft. A crank-shaft 22, mounted in boxes 23, carries a worm 24, which meshes with the worm-wheel 20, and thereby the worm-wheel is driven, imparting a rotating movement to the drill-shaft. The shaft 22 may carry, if desired, a balance-wheel 25 and is driven from a drive-shaft 26, geared with the crank-shaft 22, as shown. To the crank of the shaft 22 is attached a connecting-rod 27, and this rod is joined to a block 28, which slides on the drill-rod. On each side of the block 28 are arranged springs 29, which are fitted on the drill-rod and held in place by collars 30 fastened thereto. This imparts a reciprocal movement to the drill-rod, and the springs 29 relieve the drill-rod of the jarring effect of the blow. A spring 31 is placed on the drill-rod below the casing to stop an excessive upward blow. A boring-tool is fitted to the drill-rod in the usual manner, as illustrated in Fig. 2. It will therefore be seen that the drill-rod is driven with a combined rotary and reciprocal movement and that in addition it is gradually fed forward to its work. The drill may be adjusted to work in any direction desired and a tool of any sort applied to the rod. Manual or motive power may be employed at will.

Having thus described my invention, I claim as new and desire to secure by Letters Patent—

1. The combination of a frame-bar, a casing or the like sliding thereon, a feed-screw carried by the frame-bar, a gear-wheel having a nut formed thereon, the nut engaging the feed-screw and the gear-wheel being held on the casing to turn thereon, a drill-rod, a gear-wheel splined on the drill-rod and meshed with the first-named gear-wheel, a rotating crank-shaft, a connecting-rod between the crank-shaft and drill-rod, to reciprocate the drill-rod, a worm fastened to the crank-shaft, and a worm-wheel splined on the drill-rod and meshed with the worm.

2. The combination of a slidably-mounted

casing or framing, a drill-rod arranged therein to turn and slide, a rotating drive-shaft with a crank thereon, a connection between the crank and drill-rod to reciprocate the latter, 5 a worm on the drive-shaft, a worm-wheel held by the casing or frame and splined on the drill-rod and meshed with the worm to rotate the drill-rod, a feed-screw supported independently of the casing or framing, and a rotating feed-nut held in the casing or framing

and working with the feed-screw and driven from the worm-wheel.

In testimony whereof I have signed my name to this specification in the presence of two subscribing witnesses.

ROBERT BINNIE.
